By his Attorney,
Harlan M. Davis.

UNITED STATES PATENT OFFICE

CHARLES G. BROSTROM, OF LYNN, MASSACHUSETTS, ASSIGNOR TO UNITED SHOE MACHINERY CORPORATION, OF PATERSON, NEW JERSEY, A CORPORATION OF NEW JERSEY

METHOD OF TRIMMING HEEL COVERS

Original application filed May 21, 1927, Serial No. 193,336. Divided and this application filed June 16, 1930. Serial No. 461,439.

This invention relates to improvements in the manufacture of shoes and is herein exemplified with special reference to trimming the covers of heels, this application being a 5 division of application for Letters Patent of the United States, Serial No. 193,336, filed May 21, 1927, in my name.

In the manufacture of women's shoes, it is customary to cover the rear and the sides 10 of wood heels, for example, with a single piece of cover material commonly known as a "side cover" and to turn the top, the forward, and the bottom marginal portions of this cover over upon the attaching face, the 15 breast, and the top-lift face of the heel respectively. After the side cover together with its inturned margins has been secured to the heel, the breast of the heel is usually covered with a separate piece of material which 20 is secured to the uncovered portion of the breast and to the inturned marginal portions of the side cover. In Louis heel work the breast cover usually consists of a thin piece of leather commonly referred to as a 25 "breast flap" which is split from the heel portion of a sole and attached to the sole at the shank portion thereof. The breast cover in the finished shoe should present a smooth curve from one breast edge of the heel to the 30 other and it is therefore customary to bevel the inturned marginal portions of the side cover upon the breast of the heel in order that the edge of the inturned cover will not be visible through the thin breast cover in 35 the form of a bulge extending heightwise of the heel after the breast cover has been applied to the shoe. As a further result of this operation, the glazed grain surfaces of the inturned marginal portion of the cover 40 are removed and upset flesh surfaces of the marginal portions are provided to which portions the breast cover may be easily and effectively secured. Heretofore, the above-mentioned beveling operation has been per- 45 formed by hand, the operator making a draw cut with a drag knife first along one inturned margin of the side cover and then along the other inturned margin of the side cover. Hand beveling is slow and causes 50 many imperfections in heels since, at best,

the skiving is likely to be done unevenly. Frequently, the knife cuts through the side cover at the breast edge during the beveling operation, thereby exposing the wood heel in the finished shoe. This defect is especially 55 likely to appear if the marginal inturned portion does not adhere properly to the heel breast or where the operator is using a dull knife, since a dull knife, especially when it is moved slowly, has a tendency to drag the 60 leather during the trimming operation and to rip the same along the sharp breast edge of the heel.

In the above identified application for United States Letters Patent there is disclosed a machine constructed and arranged 65 to skive expeditiously the inturned marginal portions of side covers applied to the breast of heels and comprising a band knife, said machine having means for flexing a portion 70 of the knife to form a convex portion thereof and gages with which the breast and a side of the heel being operated upon are engaged for positioning the heel so that the inturned marginal portions of a side cover laid upon 75 the breast of the heel are trimmed by the flexed portion of the knife as the heel is guided past the knife.

In view of the foregoing, it is an object of this invention to provide an improved method of performing the above-mentioned skiving or beveling operation, by the practice of which the inturned margins of side covers secured or overlaid upon the breasts of heels may be accurately trimmed rapidly in order 80 to prepare the breasts of the heels for receiving breast covers. With this object in view my invention in one aspect comprises trimming simultaneously opposite inturned marginal portions of a heel cover laid upon the 85 breast of a heel. In carrying out my invention with the aid of the machine above referred to in its application to heels the upper breast portions of each of which projects forwardly of the heel and is convexed laterally thereof as exemplified in heels of the Louis type, the marginal portions of the cover on the lower part of each of the heel breasts, may be trimmed simultaneously by 90 cuts starting about midway between the top- 95

lift-receiving face and the attaching face of the heel and progressing toward the top-lift face of the heel. The heel may then be reversed and the marginal portions of the side 5 cover upon the upper projecting part of the breast of the heel may be beveled in successive operations by trimming cuts each starting below the place where the first cut was started and progressing toward the attaching 10 face of the heel. The steps of this method may be reversed, however, if it is found more advantageous to trim the marginal portions or one of the marginal portions of the upper part of the breast previously to trimming the 15 marginal portion at the lower part of the breast. When operating upon heels the breasts of which are not bulged laterally thereof, such as Cuban heels, for example, the inturned marginal portions of the cover 20 of the breast of the heel may be beveled simultaneously by a trimming cut progressing from one end of the heel to the other or by starting the trimming in the vicinity of the middle of the breast of the heel and working 25 toward the top-lift attaching face or the attaching face, thereafter reversing the heel and completing the trimming by simultaneously beveling the untrimmed parts of the cover margins.

30 With the above and other objects in view the invention will now be described in connection with the accompanying drawings, and pointed out in the claims.

In the drawings,

35 Fig. 1 is a perspective view illustrating the relative positions of a partially covered Louis heel and instrumentalities for positioning and trimming the marginal portions of a heel side cover which has been inturned upon the breast of the heel, the heel being shown in the process of having the lower parts of the inturned marginal portions of its side cover beveled simultaneously as the heel is moved toward the operator;

40 Fig. 2 is a perspective view illustrating the heel shown in Fig. 1 in the process of having the left upper inturned marginal portions of its side cover beveled as the heel is guided past the trimming instrumentalities;

45 Fig. 3 illustrates the heel shown in Fig. 2 in the process of having the right upper inturned marginal portion of its side cover beveled; and

50 Fig. 4 is a perspective view corresponding to Fig. 1 but illustrating a Cuban heel in the process of having inturned side cover marginal portions upon the upper part of its breast beveled simultaneously.

55 In the manufacture of shoes it is customary to apply to the rear 20 and to the sides 22 of a heel a single piece of cover material 24 commonly known as a "side cover" and to secure the top, the front, and the bottom marginal portions 26, 28, and 30 of the side cover upon the attaching face 32, the breast 34, and

the top-lift-receiving face 36 of the heel respectively. The breast 34 of the heel is then covered with a separate piece of material (not shown) extending from one breast edge 38 of the heel to the other, this cover in Louis heel work usually being in the form of a thin piece of leather split from the sole and attached thereto at the shank portion of the shoe and commonly referred to as a "breast flap".

60 In order to prevent a bulge from appearing in the breast surface of the finished heel where the breast cover overlaps an untrimmed marginal edge 40 of the inturned portion 28 of the side cover upon the breast of the heel, it is customary to bevel the inturned marginal portion of the side cover by a cut starting at the breast edge 38 of the heel and tapering to a feather edge at or near the marginal portion 40 of the inturned portion 28 of the side cover. This beveling operation, as above stated, not only improves the appearance of the breast of the heel but also trims from the inturned marginal portion of the side cover its glazed surface, thereby leaving upon the heel breast a rough flesh portion of the inturned margin to which the breast cover may be more effectively secured.

65 It has been found convenient to perform this method with the aid of the above-identified machine, only a small portion of which need be illustrated and described in this application. This machine comprises a band knife 44 having a cutting edge 46, one side of the band knife being engaged by a pair of rolls 48, 50 (Fig. 1) and the other side of the knife being engaged by a roll 52 positioned between the rolls 48 and 50 and rotatably mounted upon a bifurcated portion 54 of a holdown member 56. This holdown member may be adjusted in a path as indicated by arrows 58 in order that it will co-operate with the rolls 48, 50 to flex the cutter for forming a trimming portion 60 thereof.

70 The flexure of the band knife within limits may thus easily be changed according to the sizes and styles of heels being operated upon. In order properly to locate the heel relatively to the flexed trimming portion 60 of the knife for performing the beveling operation, the heel is positioned relatively to the flexed portion 60 of the knife 44 by engaging a side 22 of the heel adjacent to the breast edge 38 of the heel with a side gage 62 and by engaging the breast 34 of the heel with the lower surface 64 of a downwardly extending breast gage 66 secured to the holdown member 56.

75 In order to perform the trimming operation with the aid of the machine referred to, the operator presents the heel to the machine (Figs. 1 and 4) with a portion of the side of the heel adjacent to the breast edge 38 engaging the side gage 62 and the central portion of the breast of the heel engaging the

lower surface 64 of the breast gage 66. After the heel has been thus positioned relatively to the flexed portion 60 of the knife 44, the heel may be drawn toward the operator past the knife in a general direction indicated by arrow 68, while the breast of the heel is engaged against the breast gage 66 and a side of the heel adjacent to the breast edge 38 engages the side gage 62, the operator controlling the depth of the beveling cut by tipping the heel about the breast gage 66 as a pivot. The side gage 62 which is clearly described in the above-identified application is operated toward and away from the breast gage 66 through mechanism (not illustrated) by the knee of the operator during the beveling operation in such a manner as to control the position of the heel laterally thereof so that the lowest transverse section of the flexed portion 60 of the knife will be in line with the heightwise median line of the breast of the heel. By this arrangement it is possible to trim equal amounts of surplus material from each of the opposite inturned marginal portions 28 of the cover during the beveling operation.

After the lower marginal portions of the cover upon the breast of the heel have been trimmed as far as the top-lift-attaching face 36 of the heel, the heel is then turned around to a position illustrated in Fig. 2 and the left upper inturned marginal portion of the cover along the projecting portion 71 of the breast of the Louis heel is beveled by a cut starting upon the breast of the heel just below the upper part 72 (Fig. 1) of the above-mentioned cut and continuing to the attaching face 32 of the heel as the heel is drawn past the flexed portion 60 of the knife, the breast 34 of the heel and a side 22 of the heel adjacent to the breast edge 38 thereof being held in engagement with the breast gage 66 and the side gage 62 respectively during the trimming operation. In order to complete the beveling of the inturned marginal portions 28 of the cover, the heel is presented to the machine as illustrated in Fig. 3, the breast edge 38 of the heel having been lowered so that the side of the heel engages a lower portion of the side gage 62 than that shown in Fig. 2 in contact with the heel and the heel engaging the breast gage 66 adjacent to the upper right inturned marginal portion of the cover. This beveling cut is started at a position on the breast of the heel just below the upper part 76 of the first trimming cut above described and continues to the attaching face 32 of the heel as the heel is again drawn past the flexed portion 60 of the knife 44 to bevel the opposite inturned marginal portion of the cover. By starting the beveling cut at the central portion of the breast of the heel and moving the heel heightwise of itself past the knife as above described, the operator is able accurately to

control the position of the heel relatively to the knife during the operation and is able to form quickly, along the marginal inturned portions 28 of the cover upon the heel, bevels which taper uniformly from each of the breast edges 38 to the edges 40 of the cover. In operating upon a Cuban heel the operator simultaneously trims the marginal inturned portions upon the upper part of the breast as the heel is moved past the knife in a direction indicated by arrow 73 and after reversing the heel bevels simultaneously the two inturned marginal portions of the side cover upon the lower part of the breast of the heel.

While applicant has described one order of steps during the trimming of the inturned marginal portions of the cover of a Louis heel, it is clear that, as above indicated, the order of the steps may be varied so as to trim the inturned marginal portions of the cover on the upper part of the heel prior to simultaneously beveling the marginal inturned portions of the cover on the lower part of the heel or the marginal inturned portions of the cover at the lower part of the heel may be trimmed between the separate operations of trimming the upper parts of the inturned marginal portions of the cover upon the breast of the heel. In trimming Cuban heels for the purpose above described the order of operation may be varied so as to bevel simultaneously the lower inturned marginal portion of the cover previously to beveling the upper inturned marginal portion of the cover or it may be sometimes found advantageous to bevel simultaneously the opposite overlaid marginal portions of the cover by cuts progressing in one direction and starting at one end of the heel and terminating at the other end of the heel.

Having described the invention what I claim as new and desire to secure by Letters Patent of the United States is:

1. That step in the method of treating the overlaid marginal portions of a heel cover applied to the opposite lateral portions of the breast of a heel which comprises trimming simultaneously both of the marginal portions of said heel cover.
2. That step in the method of treating the overlaid marginal portions of a heel cover applied to the opposite lateral portions of the breast of a heel which comprises beveling simultaneously both of the marginal portions of said heel cover.
3. The method of treating the inturned margins of a heel cover upon the lateral marginal portions of the breast of a heel which comprises presenting the breast of the heel relatively to a trimming member and beveling simultaneously said lateral marginal portions of the heel cover.
4. The method of treating the overlaid margins of a heel cover upon the breast of a

heel which consists in beveling the marginal portions on the lower part of the breast of the heel and the marginal portions on the upper part of the breast of the heel by separate operations.

5. The method of treating the overlaid margin of a heel cover upon the breast of a heel which comprises trimming the marginal portions of the cover by trimming cuts which 10 start in the vicinity of the middle of the breast of the heel and proceed toward the attaching face and the top-lift-receiving face of the heel respectively.

6. The method of treating the inturned 15 margins of a heel cover upon the breast of a heel which comprises beveling the marginal portions on the lower part of the breast of the heel and the marginal portions on the upper part of the breast of the heel by separate operations, which progress along said 20 margins in opposite directions.

7. The method of beveling the marginal portions of a cover overlaid upon the breast of a heel, which comprises beveling the marginal portions on the upper and the lower 25 parts of the breast of the heel by separate operations, the cuts which bevel the cover starting in the vicinity of the central portion of the breast of the heel and progressing height- 30 wise of the heel.

8. The method of beveling the marginal portions of a heel cover applied to the breast of a heel, which comprises beveling the marginal portions on the upper and lower parts 35 of the breast of the heel by separate operations, the beveling operations being started at points on the heel breast which are located between the attaching face and the top-lift-receiving face of the heel and progressing 40 toward the attaching face and the top-lift-receiving face of the heel respectively.

9. The method of beveling the marginal portions of a heel side cover overlaid upon the breast of a heel, which consists in trimming simultaneously the two marginal portions of the cover on the lower part of the breast, then reversing the heel and beveling successively the marginal portions on the upper part of the breast.

10. The method of beveling the marginal portions of a heel side cover overlaid upon a heel breast which comprises beveling simultaneously the two marginal portions on the lower part of the breast of the heel and beveling the two marginal portions on the upper part of the heel by separate operations, the beveling operations starting at points near the center of the breast of the heel and progressing toward the top-lift-receiving face 55 and the attaching face of the heel respectively.

11. The method of treating the inturned marginal portions of a heel cover upon the breast of a Louis heel which consists in presenting the breast of the heel to a cutter hav-

ing a convex cutting edge and causing relative movement between the heel and the cutter for beveling simultaneously the two marginal portions on the lower concave part of the breast of the heel and beveling in separate operations the two marginal portions on the upper convex part of the breast of the heel.

12. The method of treating the inturned marginal portions of a heel cover overlaid upon the breast of a Louis heel which consists in presenting the central portion of the heel breast to a cutter having a convex cutting edge and beveling simultaneously the two marginal portions on the lower concave part 70 of the breast of the heel by cuts progressing in a direction along the breast of the heel and beveling the two marginal portions on the upper convex part of the breast of the heel by cuts progressing along the breast of the heel in a direction opposite to the direction of the first-named cuts.

13. The method of treating the inturned marginal portions of a heel cover overlaid upon the breast of a Louis heel which consists in presenting the breast of the heel to a cutter having a convex cutting edge mounted for movement lengthwise thereof and beveling simultaneously the two marginal portions on a concave portion of the breast 90 of the heel and beveling the two marginal portions upon a convex portion of the breast of the heel in separate operations each of which progresses along the marginal portions in a direction opposite to said first beveling operation.

14. The method of treating the marginal portions of a heel cover overlaid upon the breast of a Louis heel which consists in presenting the central portion of the breast of the heel to a cutter having a convex cutting edge, drawing the heel past the cutter to bevel simultaneously the marginal portions of the cover on the lower concave portion of the breast of the heel, reversing the heel, and beveling the marginal portions of the cover on the upper convex portion of the breast of the heel by two cuts which are made successively and start at the central portion of the heel breast as the heel is drawn past the cutter.

15. The method of treating the marginal portions of a heel cover upon the breast of a Louis heel which consists in presenting the central portion of the heel breast to a cutter having a convex cutting edge, drawing the heel past the cutter to bevel simultaneously said marginal portions on the lower concave part of the breast of the heel by cuts progressing during their formation in a general direction along the breast of the heel, reversing the heel, again presenting the central portion of the breast of the heel to the convex cutting edge of the cutter, and, in separate operations, drawing the heel past 110

the cutter for beveling the marginal portion of the cover on the convex part of the breast of the heel by cuts, each of which progresses in a general direction opposite to the direction in which the first-named cuts progress.

- 5 16. The method of treating the marginal portions of a heel side cover overlaid upon the breast of a heel which consists in centralizing the breast of the heel relatively to a cutter having a convex cutting edge, beveling simultaneously the two marginal portions of the cover on the central and the lower concave parts of the heel by moving the centralized heel past the cutter, reversing the heel, and beveling successively the marginal portions on the upper convex part of the breast as the heel is again moved past the cutter, the heel being positioned relatively to the cutter during the heel beveling operation by utilizing the breast and a side of the heel as gaging surfaces.

- 20 17. The method of treating the inturned marginal portions of a heel cover overlaid upon the breast of a heel which consists in presenting the central portion of the breast of the heel to a cutter having a convex cutting edge and beveling simultaneously the two marginal portions on the lower concave part of the breast of the heel as the heel is moved past the cutter by cuts progressing along the breast of the heel, and beveling the two marginal portions on the upper convex part of the breast of the heel as the heel is moved past the cutter by cuts progressing along the breast of the heel in a direction opposite to the direction of progress of the first-named cuts, said heel being presented to and moved past the cutter during the beveling operation by utilizing a side and the breast of the heel as gaging surfaces in order to remove the proper amount of material from each of the marginal portions of the cover.

45 In testimony whereof I have signed my name to this specification.

CHARLES G. BROSTROM.
